UNITED STATES PATENT OFFICE.

ASBJORN SONSTHAGEN, OF LEYTONSTONE, ENGLAND.

MACHINE FOR COATING SWEETMEATS.

Application filed March 15, 1923. Serial No. 625,298.

To all whom it may concern:

Be it known that I, ASBJORN SONSTHAGEN, a subject of the King of Norway, residing in Leytonstone, Essex, England, have invented 5 certain new and useful Improvements in Machines for Coating Sweetmeats, of which the following is a specification.

This invention relates to machines for coating sweetmeats and it refers to machines 10 of the kind in which cores or centres of suitable material are coated or covered by passing them through a stream of the coating material.

In machines of the type referred to the 15 coating material, chocolate for example, is discharged from a hopper or receptacle into a trough-like receptacle having a longitudinal opening for the escape of the material.

The present invention has for its primary 20 object certain improvements designed to prevent the clogging or choking of the discharge aperture.

The invention further provides certain 25 improvements in the construction and arrangement of the trough adapted to permit its ready removal and replacement and in the hopper supplying the material to the said trough.

In order that the invention may be the 30 better understood drawings are appended in which:—

Fig. 1 is an end view of a trough embodying the present invention.

Fig. 2 is an elevation of one of the end 35 brackets for supporting the trough, Fig. 3 is an elevation of a bracket for supporting the other end of the trough.

Fig. 4 is a front view of the trough with certain parts omitted.

Fig. 5 is a plan of the trough.

Fig. 6 is a cross-section of the trough.

Fig. 7 is a sectional view to a larger scale showing the application of the invention to an existing machine, and

Fig. 8 is a transverse section to a smaller scale than that of Fig. 7 of the trough applied to the machine.

Referring to the accompanying drawings, 1 indicates the trough into which the liquid chocolate is delivered and from which it falls in a stream upon the cores which are carried by a belt or conveyor arranged and operated in the manner usual to machines of this type.

55 The chocolate in the form of machine illustrated is conveyed from the main reser-

voir by means of the drum 2 which is partly immersed in the said reservoir said drum during its rotation passing under the inclined plate 3 whereby the chocolate is scraped from the periphery of said drum and fed onto the inner surface of the body 4. Disposed at the uppermost point of the periphery of the body 4 and engaging the inner surface of said body is a second scraper 5, whereby the chocolate is removed and falls into the end 5^a of a strainer or other receptacle 6 by which it is distributed and falls into the trough 1.

The parts just described form no part of 70 the present invention and are described merely for the better understanding thereof, the arrangement and construction of said parts being sufficiently known to those skilled in the art to render further description unnecessary.

The trough 1 is provided at the bottom with a longitudinal opening *w*, formed as will be hereafter described, in which is disposed a bar 7 of substantially inverted Y 80 section, the vertical portion 7^a of which freely enters said slot in a manner such that there is left upon each side thereof ample clearance for the passage of the chocolate.

It may here be stated that whilst chocolate is referred to as the coating material it is to be understood that other material may be used.

The bar 7 is supported at each end by means of arm 8, 9, pivoted respectively to 90 the wall or frame of the machine and the bar 10. The arms 8, 9, are each provided with a projection 11 having a bevelled face, each of which projections bear upon the face of ratchet or like wheels 12 whereby when the wheels are rotated a vertical reciprocal motion is imparted to the bars effectually preventing any clogging of the discharge aperture or trough 1. The motion of wheels 12 may be secured by mounting them upon 95 a shaft 13 supported at its ends respectively by the bar 10 and the frame or wall of the machine. The shaft passes through the wall of the machine and has at its end a chain wheel 14 around which passes a chain 100 15 passing over a second chain wheel 16 mounted on a shaft 16^a supported by brackets 16^b of the top of the machine.

It will be noted that the bar 7 constitutes 110 a flow bar or means for causing a double stream flow of the material through the slot *w*, and which bar or means extends the full

length of the slot or discharge opening and is movable laterally thereof for preventing clogging of the material during flow through the slot.

5 Motion is imparted to the shaft 13^a by a chain wheel 17 upon shaft 16^a around which passes a chain 18 operated by a chain wheel upon the shaft or spindle of body 4.

In order that the air may escape from 10 the underside of the inverted Y-shaped bar 7 and so avoid being mixed with the chocolate a perforation, indicated by *w*¹, may be formed in the end of the bar as shown more clearly in Fig. 6.

15 Preferably provision is made whereby the width of the slot or opening *w* of trough 1 may be varied within certain limits. To this end the parts or members of the trough separated by the slot *w* are pivotally mounted, that indicated by 1^a being mounted by means of pivots at its upper end upon its end walls *a* and *b* and in order that the said part may be adjusted and secured after adjustment there is pivotally connected to it a 20 link 19, Figs. 1 and 6, attached to a second link 20 pivoted upon the outer end of the trough. The connection of the two links is effected by means of a stud passing through the two links and through a radial slot in the bracket, a lock nut 22 being provided upon the outer end of the stud. 23 indicates a handle for operating the links.

The opposite side or part 1^b of the trough 25 has secured to it plates 24 Figs. 1 and 6 said part itself being pivotally mounted at its upper ends in the supporting brackets. The plates 24 Fig. 1 extend upwards beyond the upper edge of part 1^b and have 30 pivotally connected to them one end of a stud or screw 25 the end of which passes through a nut 26.

The nut 26 is recessed to engage the inner edges of a slot formed in suitably slotted extensions on the brackets *a* and *b*. By 45 turning the nut in one or other direction the part 1^b may be correspondingly tilted and the width of the opening for bar 7 varied as desired. As both parts of the trough are movable it is possible to so adjust them that the space on both sides of the 50 bar are equal.

Distance or spacing means 27, Fig. 5, is 55 provided for the end walls *a*, *b*, of the trough members, the distance between the inner faces of the said walls being such that whilst the parts 1^a and 1^b of the trough may move freely, there is not a sufficient clearance between the ends of the trough members and the inner faces of the walls to permit the chocolate to escape at these points.

Whilst the trough may be immovably mounted in the machine it is preferred to so mount it that it may be readily removed when so desired for cleaning or other purposes.

To this end there are provided brackets *c*, *d*, Fig. 7, secured respectively to the inner surface of the wall or frame of the machine and to the aforesaid bar 10.

Formed upon or secured to the inner surfaces of the brackets *c*, *d*, are projections 28, 29, 30, of triangular outline arranged as shown and designed to engage projections 31, 32, of inverted V-shaped outline formed upon the outer surfaces of the end members 75 of the trough.

The third triangular projection 30 of the brackets engage the inclined surface 33 of the strengthening flange 34 upon the outer surface of the end wall of the trough.

Obviously the construction, arrangement and method of operation of the bar 7 may be varied as desired and instead of having only vertical reciprocal motion said bar may be arranged to reciprocate transversely of 85 the opening in which it is mounted, or have both transverse and vertical motion in said opening.

Provision may be made whereby the distance from the trough to the conveyor may 90 be varied as desired.

Having thus described my invention, it should be understood that there may be modifications thereof and variations therein without departing from the spirit of the invention or exceeding the scope of the appended claims.

Claims:

1. In a machine for coating sweetmeats the combination of, an elongate trough for the coating material having a discharge opening extending lengthwise thereof; and a bar positioned in said opening and spaced away from each side of the opening extending the full length of the opening and movable laterally thereof for thereby providing double-stream flow of material through the opening.

2. In a machine for coating sweetmeats the combination of, an elongate trough for the coating material having a discharge opening extending lengthwise thereof; and a reciprocatable bar positioned in said opening and spaced away from each side of the opening extending the full length of the opening and movable laterally thereof for thereby providing double-stream flow of material through the opening and preventing clogging of the flow of material through the opening.

3. In a machine for coating sweetmeats the combination of, an elongate trough for the material having a discharge opening extending lengthwise thereof; and a bar of substantially inverted Y shape in cross-section positioned in the opening and spaced away from each side of the opening, the leg of the Y extending upwardly through the opening.

4. In a machine for coating sweetmeats

the combination of, an elongate trough for the material having a discharge opening extending lengthwise thereof; and a vertically reciprocatable bar of substantially inverted Y shape in cross-section positioned in the opening and spaced away from each side of the opening, the leg of the Y extending upwardly through the opening.

5. In a machine for coating sweetmeats the combination of, an elongate trough for the coating material having a discharge opening lengthwise thereof; a bar positioned in said opening and spaced away from each side of the opening extending the full length of the opening and movable laterally thereof for thereby providing double-stream flow of material through the opening; and means for varying the width of said opening.

6. In a machine for coating sweetmeats the combination of, an elongate trough for the coating material having a discharge opening lengthwise thereof; a reciprocatable bar positioned in said opening extending the full length of the opening and spaced away from each side of the opening and movable laterally thereof for thereby providing double-stream flow of material through the opening and preventing clogging of the flow of material through the opening; and means for varying the width of said opening.

7. In a machine for coating sweetmeats the combination of, an elongate trough having a discharge opening extending lengthwise thereof and having pivotally movable side members for varying the width of said opening; and a bar of substantially inverted Y-shape in cross section positioned in said opening and spaced away from each side of the opening, the leg of the Y extending upwardly through the opening.

8. In a machine for coating sweetmeats the combination of, an elongate trough having a discharge opening extending lengthwise thereof and having pivotally movable side members for varying the width of said opening; adjustable means for moving said side members; and a bar of substantially inverted Y-shape in cross-section positioned in said opening and spaced away from each side of the opening, the leg of the Y extending upwardly through the opening.

9. In a machine for coating sweetmeats the combination of, an elongate trough having a discharge opening extending lengthwise thereof and having pivotally movable side members for varying the width of said opening and having removably supported end walls; adjustable means for moving said side members; a vertically reciprocatable bar of substantially inverted Y-shape in cross-section positioned in said opening

and spaced away from each side of the opening, the leg of the Y extending upwardly through said opening; and means for reciprocating said bar.

10. In a machine for coating sweetmeats a trough for the coating material having an opening for the escape of the material, a bar disposed within and of less thickness than the width of the opening, pivotally mounted arms supporting said bar, projections upon said arms, ratchet wheels engaging said projections, means for imparting motion to said ratchet wheels, brackets for supporting said trough, and inter-engaging projections upon the inner faces of said brackets and the outer faces of the end members of the trough.

11. In a machine for coating sweetmeats a trough for the coating material comprising end members and two longitudinal members relatively adjustable with respect to each other for providing a space between the lower ends of said members, a body disposed in said space and means for imparting vibratory movement to said body, brackets for supporting said trough, and inter-engaging projections upon the inner faces of said brackets and the outer faces of the end members of the trough.

12. In a machine for coating sweetmeats a trough for the coating material comprising end members and two longitudinal members pivotally mounted at their upper ends to said end members of the trough for providing a space between the lower ends of said members through which the coating material escapes, vertical projections upon one member, screws pivotally secured to said projections, slotted projections upon the end members of the trough engaging nuts upon the screws whereby the member may be rocked upon its pivot, a link connected to the second member, a second link connected to one of the ends of the trough, a screw connecting said links and passing through a radial slot in said end member, a nut upon said screw for clamping the links, a body disposed in the opening between the longitudinal members of the trough, means for imparting a vibratory motion to said body brackets for supporting said trough, and inter-engaging projections upon the inner faces of said brackets and the outer faces of the end members of the trough.

In testimony whereof I have hereunto set my hand in the presence of two witnesses.

ASBJORN SONSTHAGEN.
